UNITED STATES PATENT OFFICE.

JOHN H. SMITH, OF PHILADELPHIA, PENNSYLVANIA, ASSIGNOR TO WESTINGHOUSE ELECTRIC AND MANUFACTURING COMPANY, A CORPORATION OF PENNSYLVANIA.

CONDENSER.

Application filed March 3, 1923. Serial No. 622,574.

My invention relates to surface condensers and it has for an object the provision of apparatus of the character designated which shall deliver non-condensable fluids to the 5 non-condensable fluid-withdrawal means at a low temperature and specific volume, and which shall, at the same time, deliver to the hot well condensate of a temperature substantially that of the steam.

10 It has for a further object the prevention of re-evaporation of the condensate within the hot well. These and other objects and advantages of my invention are attained by the structure hereinafter described and illustrated in the accompanying drawings, in which Fig. 1 is a transverse sectional view of a preferred embodiment of my invention taken on the line I—I of Fig. 2; Fig. 2 is a longitudinal sectional view taken on the line 15 II—II of Fig. 1; Fig. 3 is a partial transverse sectional view thereof taken on line III—III of Fig. 2 and Fig. 4 is a transverse sectional view of another embodiment of my invention, showing a rearrangement of the tubes 20 within the condensing chamber.

Surface condensers of the so-called radial-flow type, shown and claimed in United States Patent No. 1,142,784, issued to Westinghouse Machine Company on June 8, 1915 25 on application filed by Raymond N. Ehrhart, have the distinct advantage of providing a heat-transmitting surface of high efficiency by reason of the large entrance area presented to the steam entering the tube nest, and a short 30 path of travel of the air to the air off-take. This arrangement insures there will be no appreciable variation in pressure between the steam inlet and the point of complete condensation.

35 Efficiency in the operation of condensers demands, in addition, that the energy expended in the withdrawal of non-condensable fluids shall be reduced to a minimum. This result is most readily accomplished by reducing the volume of fluids necessary to be handled by the air-removing means prior to the 40 delivery thereto.

In my improved construction I effect the 45 above results by providing a condenser of the radial-flow type having an air-cooling chamber disposed without and contiguous to the condenser shell. The non-condensable gases are conveyed from the condenser to the air-cooling chamber by means of a conduit having its inlet disposed well within the nest of

condensing tubes. The air-cooling chamber is provided with a plurality of cooling tubes over which the air is drawn prior to its removal by the air ejectors. In its passage through the chamber, a large portion of vapor entrained in the air is condensed and separated therefrom, and the temperature and specific volume of the air is considerably reduced.

50 Efficiency in the operation of condensers is still further increased by reducing the amount of re-evaporation of the condensate in the hot well. In my improved construction I provide a hot well for the reception of condensate and with a condensate outlet 60 which communicates freely with the condensing chamber and through water-seal means with the air-cooling chamber, whereby the passage of uncondensed fluids from the air cooling chamber to the condensate outlet is 65 prevented. Re-evaporation of the condensate in the hot well is reduced to a minimum by having the condensed fluid from the air-cooling chamber flow through the water seal and mingle with the condensate from the 70 condensing chamber. As the temperature and pressure of the condensate from the condensing chamber are slightly higher than those of the condensate from the cooling chamber, the mixture of the two as stated 75 above, is unproductive of re-evaporation.

80 Referring to the drawings for a more detailed understanding of an apparatus embodying my invention, I have indicated at 10 a condenser comprising a condensing chamber 11 and an air-cooling chamber 12, and having a shell 13 and a supplemental shell 14. The shell 13 is provided with a steam inlet 15, condensate outlets 16, and an eccentrically arranged nest of tubes 17 within the 85 shell and engaging the tube sheets. It will be noted that the condensing tubes are spaced from the sides of the shell and form steam delivery passages 18 and 19, communicating with the steam inlet 15, and surrounding the 90 group of condensing tubes 17. The air-cooling chamber 12 is provided with an inlet 20 (shown in Fig. 3), air outlets 21, condensate outlets 22 and a plurality of cooling tubes 23. A hot well 24 is secured to the supplemental 95 shell 14. Water boxes 25, joined to the tube sheets and shell, are provided in the usual manner. The condensing chamber 11 communicates with the hot well 24 through the openings 16 in the lower portion of the shell 13, 100 105

and the condensate is conveyed to the hot well 24 by the conduit 27. There is no communication between the air-cooling chamber 12 and the lower portion of the condensing chamber 11.

All air and non-condensable gases are conveyed to the air-cooling chamber by means of a conduit 28 having a hollow portion 29. This conduit extends the longitudinal length 10 of the condensing chamber and is secured to the shell 13, and communicates throughout its entire upper portion 30 with the condensing chamber 11 for the admission of non-condensable gases. The entire lower portion of 15 the conduit communicates at 20 with the cooling chamber 12, as shown in Fig. 3, except in the vicinity of the condensate outlets, 16 across which the hollow portion 29 of the conduit 28 is blanked in order to cut 20 off free communication between the central or air off-take portion of the condensing chamber and the hot well. The hot well 24, which is secured to the supplemental shell 14 by means of a flange 32, comprises a discharge compartment 33 freely communicating 25 with the condensing chamber 11, and a collection compartment 34 which in turn communicates with the air-cooling chamber 12. The hot well is provided with an inner 30 upstanding sleeve 35 and an outer downwardly-extending sleeve 36, which makes a tight joint 37 at its upper end with the conduit 27. The inner upstanding sleeve 35 terminates within the hot well 24 above the 35 lower edge of the outer downwardly-extending sleeve 36 and defines a water seal. Condensate collected in the hot well is discharged to a suitable condensate pump through an outlet 38.

Having described the arrangement of an apparatus embodying my invention, the operation thereof is as follows: Steam from a turbine or other prime mover is admitted into the condensing chamber through the steam inlet 15 and passes within the shell 13 in such a manner as to substantially surround the cooling tubes within the condensing chamber. The cylindrical entrance to the tube nest is enabled to accommodate a large 40 volume of steam readily, and the steam passes radially through the nest of tubes toward the inlet or upper portion 30 of the air conduit. The steam is almost completely condensed in the passage over the tubes and the 45 non-condensable gases, which have a small condensable fluid content, pass through the hollow portion 29 of the conduit 28 and flow downwardly and enter the separate air-cooling chamber 12 at its inlet 20. At 20, it diverges into two streams and is drawn upwardly over the cooling tubes 23 having first pass cooling water circulating therethrough, and the gases are dried and cooled. The air is withdrawn through the outlets 21 50 by means of a suitable pump. The condensate

dripping from the cooling tubes 23 of the air chamber, falls to the bottom of the shell 14 and thence through the openings 22 into the collection compartment 34 of the hot well 24, after which it mingles or unites 70 with the condensate from the condensing chamber, as will hereinafter be more fully described.

Condensate collects in the bottom of the condensing chamber 11 adjacent to the outside surfaces of the conduit 28 and passes through the openings 16 into the conduit 27, which conveys it to the discharge compartment 33 of the hot well 24. The condensate flowing from the air-cooling chamber 12 through the openings 22 falls into the collection compartment 34 and forms a water or hydrostatic seal, thereby preventing a direct flow of air or steam from the condensing chamber to the air-cooling chamber, because 80 of the relatively lower pressure prevailing within the latter chamber except after it passes to the interior part of the condensing chamber in its region of lowest pressure and temperature. It further prevents the passage of vapors generated in the hot well to the air-cooling chamber. The water in the collection compartment 34 exposed to the pressure of the air-cooling chamber 12, will assume a slightly greater depth of liquid than 85 that of the water exposed to the pressure of the condensing chamber 11. The condensate within the collection compartment 34 passes into the discharge compartment 33 wherein it unites with the condensate from the condensing chamber 11. The discharge compartment 33, having a relatively higher pressure and temperature therein due to its free communication with the condensing chamber 11, the entering of the relatively colder 90 condensate thereinto is not conducive to evaporation. All condensate is withdrawn from the discharge compartment 33 through the port 38 by any suitable pump.

Fig. 4 discloses a modified form of my invention in which the upper portion of the tube nest within the condensing chamber is spaced from the walls of the shell, defining therewith steam passages, while the lower portion is spaced in close proximity to the shell, the arrangement of the tubes within said shell being such as to define a partial radial flow and a partial downflow or what will be termed a multi-flow condenser.

The advantage of this type of condenser is 100 its increase in capacity, due to the additional cooling surface therein as compared with a condenser of a type shown in Fig. 1 of equal physical proportions. This increase in capacity, however, is at the expense of a slight 105 decrease in efficiency, which decreased efficiency is nevertheless superior to that obtained in condensers of the straight-downflow design.

Referring to the drawings for a more de- 110

tailed understanding of this form of my invention, I have indicated, at 40, a condenser comprising a condensing chamber 41 and an air-cooling chamber 42 and having a shell 43 and a supplemental shell 44. The shell 43 is provided with a nest of tubes 45, a steam inlet 46, and condensate outlets 47 communicating with a hot well 50. The upper portion of the tube nest 45 is spaced within and from the sides of the shell 43 and forms steam delivery passages 48 and 49 therewith, which passages communicate with the steam inlet 46. In the lower portion of the condensing chamber 41, the tubes are spaced in close proximity to the shell 43, this portion of the chamber representing substantially a down-flow condenser. Air and non-condensable gases are conveyed from the condensing chamber 41 to the air-cooling chamber 42 by means of a conduit having sides 51 and a hollow portion 52. This conduit extends the longitudinal length of and is secured to the shell 43. It communicates throughout its entire upper length 53 and through a plurality of circular openings 55, with the condensing chamber 41 for the admission of non-condensable gases. These gases are discharged throughout its entire lower length 54 to the air-cooling chamber 42, except in the vicinity of the condensate outlets 47, across which the hollow portion 52 of the conduit 51 is blanked in order to cut off free communication between the central or air off-take portion of the condensing chamber 41 and the hot well 50. The remaining structure of this embodiment of my invention is similar to that described in reference to Figs. 1, 2 and 3.

The operation of the above arrangement of my apparatus is as follows: Steam from a turbine or other prime mover is admitted into the condensing chamber through the steam inlet 46 in such manner as to substantially surround the upper portion of the condensing tube nest 45. A portion of the steam passes radially through the nest of tubes toward the opening 53 of the air off-take conduit 51, while the remaining portion flows downward and through the tube nest 45 toward the circular openings 55 in the lower portion of the air off-take conduit. The steam is almost completely condensed in the passage over the tubes and the non-condensable gases, which have a small condensable fluid content, pass through the hollow portion of the conduit and flow downwardly and enter the separate air-cooling chamber at its inlet 54. The condensate dripping from the cooling tubes within the condensing chamber collects in the lower portion thereof adjacent to the outer surfaces 51 of the conduit and passes through the openings 47 into the hot well 50. The remaining features of the complete cycle of operation of this embodiment of my invention are similar to that heretofore described with reference to Figs. 1, 2 and 3.

While I have shown my invention in but two forms, it will be obvious to those skilled in the art that it is not so limited, but is susceptible of various other changes and modifications without departing from the spirit thereof, and I desire, therefore, that only such limitations shall be placed thereupon as are imposed by the prior art or as are specifically set forth in the appended claims.

What I claim is:

1. In a surface condenser, a condensing chamber having a region of relatively low pressure and temperature and a region of relatively higher pressure and temperature, a hot well having a condensate outlet, an air cooling chamber isolated from the condensing chamber and communicating only with the region of low pressure and temperature in the condenser, and water seal means between the air cooling chamber and the condensate outlet.

2. In a condenser, the combination with a shell having a fluid inlet port, of a nest of condensing tubes therein, an air-cooling and drying chamber without the shell and contiguous thereto, a nest of tubes therein, a hollow wall for the conveyance of non-condensable fluid extending the length of the shell and communicating with an inner portion of the condensing tube nest and the air-cooling chamber, a hot well for condensate associated with the lower portion of the shell, said hot well communicating with a lower portion of the air-cooling chamber, and air outlet means provided in the cooling chamber remote from its communication with the hollow wall, a condensate outlet, and water seal means between the condensate outlet and the air outlet.

3. The combination, with a surface condenser comprising a shell having a motive fluid inlet and a nest of condensing tubes within the shell, of an air cooling and drying chamber outside the shell, a nest of cooling tubes within said cooling and drying chamber, means for passing uncondensable fluid from the condensing tubes to the cooling tubes, a hotwell for receiving condensate from the shell, said hotwell having a condensate removal port, and means providing a liquid seal between said condensate removal port and the air cooling and drying chamber.

4. The combination, with a radial flow condenser comprising a shell having a motive fluid inlet, a nest of tubes within the shell, and an air and non-condensable gas offtake extending within the nest of tubes, of a tubular cooler outside of the radial flow condenser and in communication with the air and non-condensable gas offtake of the radial flow condenser, a hotwell arranged to receive condensate from the radial flow condenser and from the cooler, said hotwell having a condensate removal port, and means providing a

liquid seal between said condensate removal port and said cooler.

5. The combination, with a surface condenser comprising a shell having a motive fluid inlet, a nest of tubes within the shell, and an air offtake extending within the nest of tubes, of a supplemental shell contiguous to said first-mentioned shell and arranged to define therewith a cooling chamber for air and non-condensable gases, a bank of tubes within the cooling chamber, said first-mentioned shell having ports for affording communication between the cooling chamber and the air offtake, a hotwell for receiving condensate from the cooling chamber and from the condenser and arranged to be secured to said supplemental shell, an upstanding cylindrical wall within said hotwell arranged to define the condensate removal port therefor, and a cylindrical wall member depending from said first-mentioned shell through the cooling chamber and into the hotwell, the lower portion of said depending wall encompassing the upper portion of said upstanding wall, whereby said cylindrical wall members and the hotwell define a liquid seal between the cooling chamber and the condensate removal port of said hotwell.

6. The combination, with a surface condenser comprising a shell enclosing a condensing compartment, of a cooling compartment outside the shell and contiguous thereto and means providing a liquid seal between the respective compartments.

35. 7. The combination, with a surface condenser comprising a shell enclosing a condensing compartment, of a cooling compartment outside the shell and contiguous thereto, a connection for passing air and non-condensable gases from the condensing compartment to the cooling compartment, and means including a liquid seal for passing condensate from the cooling compartment.

45. 8. The combination, with a surface condenser comprising a shell enclosing a condensing compartment, of a cooling compartment outside the shell and contiguous thereto, a connection for passing air and non-condensable gases from the condensing compartment

50. ment to the cooling compartment, a common hotwell for receiving condensate from both compartments, and means within the hotwell providing a liquid seal for preventing the by-passing of gaseous media from one compartment to the other through the hotwell. 55

9. The combination with a surface condenser comprising a shell enclosing a condensing compartment, of a cooling compartment outside the shell, means providing a 60. passageway for gaseous media from the condensing compartment to the cooling compartment, means providing a common outlet for condensate from condensing compartment and from the cooling compartment, and means providing a liquid seal between the 65. cooling compartment and said common outlet.

10. The combination with a surface condenser comprising a shell enclosing a condensing compartment and having an inclined 70. lower portion, of a cooling compartment outside the shell and having an inclined lower portion and an upper portion substantially complementary to the inclined lower portion of the condensing compartment, means 75. providing a common outlet for condensate from the lower portion of each of said compartments, means providing a liquid seal between the cooling compartment and the common outlet, and means providing a passageway between said compartments and above 80. the seal for conducting gaseous media from the condensing compartment to the cooling compartment.

11. The combination with a surface condenser comprising a shell enclosing a condensing chamber, of a cooling chamber outside of the shell, means providing a passageway between said chambers for gaseous media, means providing a condensate off-take 85. from the condensing chamber and means below said passageway providing a liquid seal 90. for discharging condensate from the cooling chamber to said off-take.

In testimony whereof, I have hereunto subscribed my name this 28th day of February, 1923.

JOHN H. SMITH.
